PROCESS OF MAKING PAPER
RECEPTACLES

George W. Poppe, Brooklyn, N. Y., assignor to
Equitable Paper Bag Co., Inc., Brooklyn, N. Y.,
a corporation of New York

Original application June 26, 1934, Serial No.
732,494. Divided and this application April 29,
1935, Serial No. 18,751

2 Claims. (Cl. 93—35)

This invention relates to a process of making a paper receptacle designed more especially for holding merchandise for mailing purposes which requires inspection by the postal authorities. In my application Serial No. 732,494, filed June 26, 1934, and allowed October 9, 1934, I have shown, described and claimed a paper receptacle of this type. The present case is a division of said application.

10 An essential feature of the receptacle structure described and claimed in the parent application is the provision of tapered flaps at the open end of the bag which enables them to be folded inside the receptacle and to be readily inserted between the leaves of a pamphlet, magazine or the like to thereby securely hold the same within the receptacle, thus rendering unnecessary the employment of several closure devices, at the same time permitting ready inspection of 15 the contents without withdrawing the flaps. The flaps must therefore be of the proper length in order that the result sought may be accomplished.

The process by which this receptacle may be conveniently and rapidly produced will be better 20 understood by reference to the following description when taken in connection with the accompanying drawings in which—

Figure 1 is a perspective view of my improved receptacle ready for use;

25 Figure 2 is a longitudinal sectional view through the receptacle, showing how the flaps are folded and inserted between the pages of a magazine contained within the receptacle;

Figure 3 is a front elevation of the upper portion of the receptacle with parts broken away to show how the tapered flaps enable the same to be inserted within the pages of a magazine;

30 Figures 4 and 5 are views showing some of the steps in the process of making my improved receptacle and

Figure 6 is a longitudinal section through a bag machine showing how the article is produced on such a machine.

The method of making the receptacle is illustrated in Figures 4, 5 and 6. Referring to Figure 45 5, a web of paper 16 to which a line of paste 17 has been applied is folded to form a bag tube, which tube is severed into bag lengths in a manner well known in the art of bag making. Preferably this folding, pasting and severing is done 50 on an ordinary bag machine and in Figure 6 I have shown more or less diagrammatically a cross-section of such machine with the necessary additions and modifications which fit it to carry 55 out the preliminary steps in the making of my

improved receptacle. Referring to this figure, the web 16 is fed from a roll of paper 18, which web, after passing suitable guiding rollers, is fed to the reversing roller 20, at which point the line of paste 17 is applied by a paste disc 22 revolving 5 in a paste pot 23. From the roller 20 the web passes under the heel of a former 24 and is drawn along by the usual feed rollers 26. The edge of the former is serrated at 28 and there is the usual lip knife 30 also having a serrated 10 edge. After passing the feed rollers, the bag tube is led between the usual pinch bars 32 which momentarily retard it at the same instant a striker bar 34, carried by a sprocket chain 35, delivers a sharp blow to the tube from beneath. 15 After a bag section is severed from the tube and at the instant the pinch bars free it, the severed bag section is pulled forward by scoring devices 36, which devices make the score line 40. The bag then passes to the usual cylinders 38 20 which fold and paste the bottom.

The upper cylinder is provided with the usual paste bar 39 which receives paste from a roller 40 rotating the paste supply vessel 41, all of these parts being of the usual construction and found 25 in an ordinary bag machine. The lower cylinder 38 carries the usual clamp 42 with which cooperates the tucker blade 43 by which the bag bottom is folded. The finished bag then passes to the usual delivery mechanism indicated generally 30 by 44.

When the web is passing over the roller 20 a die 46 carried by the shaft 47 suitably driven from the lower pinch bar shaft 33 makes an incision in the web, said incision eventually forming the 35 notch 42, Figures 1 and 2. The incision is also indicated as 42 in Figure 5. The bag, after being severed by the striker bar 34 and before the bottom is folded by the cylinders 38 has the appearance depicted at the left, Figure 5. It will 40 be noted that the lower serrated edge 48 of the seam wall is offset from the lower wall so that when the tube section is folded along the line a—a, Figure 5, a portion of the seam wall is included within the fold. This gives a reinforced 45 bottom which is peculiar to a bag as distinguished from an envelope. The line of paste applied by the bar 39 is indicated at 49, Figure 5.

It is to be understood, of course, that the timing of the various parts of the machine is such 50 that the score line 40 is made at the proper place.

After the bag tube section has passed the cylinders 38, it has the appearance shown in Figure 4.

In order, however, to produce the bag shown 55

in Figure 1, further operations are necessary. These consist in cutting the bag tube transversely along a line *b*—*b* which is within the serrations 50, Figure 4. This operation may be performed 5 with an ordinary paper cutter. The edges of the bag are also cut along the lines *c*—*c* and after this cutting operation the bag presents the appearance shown in Figure 1. The angle at which the cuts *c*—*c* are made may, of course, be varied 10 as desired.

Where the two flaps 6 and 8 are of equal length then it is convenient to provide the notch 12 in one of these flaps for convenience in opening the bag mouth. The incisions which create these 15 notches, each of which is made by the die 46, are at bag length intervals apart and the timing may be such that when the tube is severed along the line 50, Figure 5, such line of severance will be just above the ends of the incision. This 20 position of the incision prevents a tab appearing at the end of the flap of the finished bag. While this necessitates a trifle more waste of paper when the bag is cut off along the line *b*—*b*, Figure 4, the finished bag has a better appearance.

25 When the flaps are not required to be of equal length, the cuts along the line *b*—*b* may be dispensed with, only the cuts *c*—*c* being made.

The method by which the bag is produced is likewise inexpensive, the preliminary steps be-

ing performed on an ordinary bag machine. The final steps may be performed by an ordinary paper cutter, although provision may be made, if desired, to make the cuts *c*—*c* on the bag machine.

I claim:—

1. The process of making a paper receptacle which consists in folding a web of paper to form a bag tube with the edges of the web overlapping to form a seam, pasting the seam, severing the tube into bag lengths so that the tube walls are offset in the direction of the tube length, folding and pasting the bottom and cutting the edges of the tube along diagonal converging lines to form two flaps at the top of the bag. 15

2. The process of making a paper receptacle which consists in folding a web of paper into a bag tube with the edges of the web overlapping to form a seam, pasting the seam, severing the tube into bag lengths so that the walls of the tube 20 are offset in the direction of the tube length, folding and pasting the bottom with portions of the seam wall included within the fold, cutting the edges of the tube along diagonal converging lines and also cutting the top of the tube transversely, thereby to form two flaps at the top of the bag. 25

GEORGE W. POPPE.
